Primary Examiner — Ricky Pham(74) *Attorney, Agent, or Firm* — Workman Nydegger**CLAIM**

The ornamental design for a chair, as shown and described.

DESCRIPTION

FIG. 1 is an overhead front perspective view of a chair showing our new design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a top plan view thereof;

FIG. 7 is an overhead front perspective view of a second embodiment of the chair;

FIG. 8 is a front elevational view thereof;

FIG. 9 is a left side elevational view thereof;

FIG. 10 is a rear elevational view thereof;

FIG. 11 is a right side elevational view thereof; and,

FIG. 12 is a top plan view thereof.

The broken lines showing features of the design are for the purpose of illustration only and form no part of the claimed design.

1 Claim, 12 Drawing Sheets(56)
